UNITED STATES PATENT OFFICE.

GEORGE H. PHILLIPS, OF TROY, NEW YORK, ASSIGNOR OF ONE-HALF TO
WALTER A. CLARK, OF SAME PLACE.

STOVE-SUPPORT.

SPECIFICATION forming part of Letters Patent No. 270,978, dated January 23, 1883.

Application filed July 26, 1882. (No model.)

To all whom it may concern:

Be it known that I, GEORGE H. PHILLIPS, a citizen of the United States, residing in the city of Troy, in the county of Rensselaer and State of New York, have invented certain new and useful Improvements in Stove-Supports, described and set forth in the following specification, reference being had to the accompanying drawings, in which—

10 Figure 1 is a perspective view of a stove-leg having a part of my invention embodied therewith. Fig. 2 is a perspective view of a section of my improved base-ring, showing other parts of my invention. Fig. 3 is a cross-section of a ring and leg combined. Fig. 4 is a perspective view of my improved base-supporting ring mounted with legs; and Fig. 5, a detail perspective view of a portion of the supporting ring, showing the overlapping joint and upper 20 and lower shoulders.

This invention relates to certain improvements in stove-supports, and it has for its object to provide a cheap and durable means for supporting the body of the stove, as more 25 fully hereinafter set forth.

B is a stove-leg on which are formed the nibs *a a* and an offset shank, K, in which I make a hole or elongated slot, S, and notches *t t*. In Fig. 2, H is a part of my improved base-ring, in which *w* is a projection extending inwardly from the periphery of such ring, and having the hole *r* in said projection, and *o o* are nibs on the extreme edge thereof; and *h h'* represent shoulders, the upper one of which is 35 a guide and support to the base of a stove when placed within it.

R is a projection having the hole *N* cast therein and an underlapping flange, *g*, formed on one end of the section, while at the other 40 or opposite end are the same counterparts, which are made to overlap, and by which they are joined together and held with an ordinary stove-bolt passing through the hole *N*, as seen in Fig. 4.

45 In Fig. 3, Y is a stove-bolt, and *j* a nut, and

c an offset or rest in the leg B, on which the ring or section of the ring H rests, and when bolted together, as shown in Figs. 3 and 4, the nibs *a a* engage with the inner and under side of the ring, while the nibs *o o* on the projection *w* lock into the recesses *t t* of the stove-leg B, whereby they are firmly secured in position, and the ring is flush with the face of the leg, as shown.

In Fig. 4 are two sections of rings mounted with stove-legs in their respective positions ready for the base of a stove, which may be placed upon the ring within the raised flange *h*, and by which the mechanical construction, bolts, screw-heads, &c., are hidden from view, and a neat and durable stove-base is provided.

Having thus described my invention, what I claim is—

1. In a stove-support, the sectional ring consisting of the segmental sections, each being 65 provided with a double-shouldered overlapping joint and lug at one end, and a corresponding depression and lug at the other, the said sections being secured together by bolts passing through the lugs, substantially as shown.

2. In a stove-support, the sectional ring having double-shouldered overlapping joints and lugs, united by means of bolts, and inwardly-projecting lugs or projections, to which the legs are secured, substantially as specified.

3. The combination, in a stove-support, of the sectional ring having a flange at its upper edge and overlapping joints and projections, and means for securing them together, and inwardly-extending lugs or projections, with the 80 legs having their shanks adapted to be secured to the inwardly-extending lugs, and provided with an offset for receiving the lower edge of the ring, substantially as specified.

In testimony whereof I hereunto set my hand 85 in presence of two subscribing witnesses.

G. H. PHILLIPS.

Witnesses:

WM. C. GEER,

JOHN H. GOODFELLOW.
